UNITED STATES PATENT OFFICE.

WILLIAM CECIL BOWER, OF BIRMINGHAM, ALABAMA.

DESIGN FOR A STAMP.

SPECIFICATION forming part of Design No. 24,382, dated June 11, 1895.

Application filed March 28, 1895. Serial No. 543,588. Term of patent 3½ years.

To all whom it may concern:

Be it known that I, WILLIAM CECIL BOWER, a citizen of the United States, residing at Birmingham, in the county of Jefferson and State of Alabama, have invented a certain new and original Design for a Stamp; and I do declare the following to be a full, clear, and exact description of the invention, such as will enable others skilled in the art to which it appertains to make and use the same, reference being had to the accompanying drawing, which forms a part of this specification.

My design comprises a stamp having upon its face the pattern shown in the accompanying drawing, which forms a part of this specification.

The leading and characteristic feature of the design comprises a group of three fish, the fish comprising the group being three in number and each of the fish having sharp pointed heads and the fish having their bodies covered with scales. The fish are overlapped

and so placed that the lines forming the under side of the fish from the extreme end of the nose to the longitudinal center of the fish will coincide at the central point of the group; thus producing clearly defined isosceles triangles about the central point of the group, while the sharp pointed noses of the three fish will coincide with the circumference of a circle having its center at the central point of the group.

Having thus described my design, what I claim to be new, and desire to secure by Letters Patent, is—

The design for a stamp, substantially as herein shown and described.

In testimony whereof I affix my signature in presence of two witnesses.

WILLIAM CECIL BOWER.
